E. H. MOYER

HEADLIGHT SIGNAL

Filed Aug. 26, 1924

Earl H. Moyer
Inventor,

by

Edgar C. Moyer
Attorney

UNITED STATES PATENT OFFICE.

EARL H. MOYER, OF READING, PENNSYLVANIA.

HEADLIGHT SIGNAL.

Application filed August 26, 1924. Serial No. 734,151.

To all whom it may concern:

Be it known that I, EARL H. MOYER, a citizen of the United States, residing at Reading, in the county of Berks and State of Pennsylvania, have invented certain new and useful Improvements in Headlight Signals, of which the following is a specification.

This invention relates to improvements in headlight signal devices and it is intended more particularly for use on the headlights of an automobile.

Inasmuch as the laws require that the headlights of a vehicle be lighted at certain times, it is important that the driver be able to determine whether his lights are on or off at all times, and to this end I have devised a simple means of conveying this information.

20 The invention consists of a relatively small reflector attached to the upper portion of the lens rim of the headlight, in such position that the driver will be sure to get a reflection of the lighted lamp—25 and, whereby he will be informed, when he does not get such reflection, that the lamp in that particular headlight has gone out.

The invention is more fully described in the following specification and clearly illustrated in the accompanying drawing, in which:—

Figure 1 is a side elevational view of a headlight of ordinary construction, with my device in position thereon.

35 Figure 2 is a front elevation thereof.

Figure 3 shows the reflector itself in elevation, ready to be applied to the headlight, and

40 Figure 4 is a vertical central section through Fig. 3.

The numeral 1 designates a headlight having the usual lens rim 2.

The numeral 4 designates the body of my reflector, which is preferably cut from a flat sheet of light metal, with four integral fingers 5, by means of which the device, when bent to proper form, is attached to the lens rim.

45 The body portion is formed with a depending portion 6, which is bent to curved

position: as shown in Fig. 4, and which forms the reflector. The upper portion of the blank is bent to form a substantially rectangular box-like member, 7, and this is preferably provided with a colored transparency 8 which may preferably be held in position by a spring 9.

When the blank is bent to the form designated, that is, the lower portion curved to form the reflector and the upper portion bent to form the signal box, with the transparency in position, the fingers 5 are bent about the lens rim to secure the device in position centrally at the upper edge of each headlight, and the rays of light from the lamp will strike the reflector and show through the colored transparency which faces the driver of the vehicle, so that he will be constantly informed as to whether or not the lamp is burning.

It is evident that the blank from which the combined reflector and signal box is formed, may be made integrally with the lens rim if desired, but I have shown it in the form illustrated and described, as the preferred form of device which may be easily applied to any headlight.

Having thus described the invention, what I claim and desire to secure by Letters Patent is:

1. The combination of a headlight having a lens rim, with a signal device formed with flexible fingers for attachment to the lens rim, said device consisting of a sheet of metal having its lower extremity curved to form a reflector, and its upper portion bent to form a substantially rectangular box, and a colored transparency located within said box and a spring to keep the transparency in position.

2. A headlight reflector made of a single sheet of thin metal, formed with a plurality of flexible securing fingers, having its lower portion curved to form a reflector and its upper portion bent to form a rectangular box, a colored transparency located within the box and spring means for holding said transparency in position.

In testimony whereof I affix my signature.

EARL H. MOYER.
